SAND CONDITIONING APPARATUS

Stanley B. Davies, Kingston, Pa., assignor to
Royer Foundry and Machine Co., Kingston, Pa.,
a corporation of Pennsylvania

Application December 24, 1936, Serial No. 117,609

13 Claims. (Cl. 259—144)

This invention relates to conditioning apparatus and particularly to that type which reconditions material, by first passing it through a screening and a scrap removing device which removes metal and other foreign matter, and then through a treating and blending device which breaks up the material and discharges it thoroughly reconditioned.

It is here shown as adapted to the reconditioning of molder's sand, although it may obviously be used with other materials.

The primary object of the present invention is to associate the screening device and the sand treating device so that they may be operated as a unit or individually, as may be desired, and thus provide greater flexibility of the apparatus than has heretofore been possible.

With the foregoing and other objects in view, the invention will now be more particularly described, reference being had to the accompanying drawings, wherein:

Figure 1 is a side elevation of the sand conditioning apparatus.

Figure 2 is a section taken on line 2—2 of Figure 1.

Figure 3 is a modification of the front of the frame showing the front locking element.

Figure 4 is a section taken on line 4—4 of Figure 2.

Figure 5 is a section taken on line 5—5 of Figure 1.

Figure 6 is a section taken on line 6—6 of Figure 2.

Figure 7 is an enlarged fragmentary view of the rear portion of the sand treating device, and

Figure 8 is an enlarged fragmentary view of the weight lifting mechanism of the screening device.

Generally, the present sand conditioning apparatus comprises a rectangular open frame structure supporting an upper screening and scrap removing device. The lower portion of the frame also houses a sand treating and blending device. The discharge spout of the screen is positioned to direct the material into the hopper of the sand treating and blending device where it falls upon a sand treating belt which breaks up the material and discharges it in a stream from the upper end of the belt. The base of the frame is so designed as to combine readily with and rigidly retain the sand treating device in operative relation to the screen and scrap remover, but at the same time permit the former to be released from its frame in order that it may be used as a separate unit

wherever desired. This is accomplished by removing a section of the base which locks the device in operative position in the frame.

Referring now to Figure 1, there is disclosed one embodiment of the invention wherein the numeral 10 designates the open frame which houses and fixedly supports the screen and sand treating device. This frame is preferably made up of vertically extending spaced frame members 11 of angle iron formation, upper and lower horizontal frame members 12 and 13, and intermediately spaced horizontal frame members 13'. These latter frame members, together with suitable interiorly arranged frame members 14 are designed to support the screening and scrap removing device 15. This device comprises two sets of screening units 16 and 17 and material retarding weighted levers 18 positioned above the screening units. A hopper 19 is provided for directing the sand or other material to the screening units and this comprises a plurality of inclined plates having their upper ends secured to the top frame members 12 and diverging inwardly and downwardly to a point above the screening units.

The screening device is provided with a discharge hopper 20 projecting downwardly below the intermediate frame members 13' and so positioned as to direct the material into the hopper 21 of a sand treating and blending device 22. This device includes, in addition to the hopper 21, a sand receiving and treating belt 23, which is operated at a high rate of speed in order that the sand may be completely broken up, conditioned, and then thrown outwardly and discharged from the upper end of the belt.

The belt is mounted in a frame 24 carrying a rear axle 25 upon which are journaled rollers 26. At the front of the frame is a swivel casing 27 which supports a swivel 28. This swivel carries 40 at its lower end an axle 29 which has mounted thereon front rollers 30.

The base of the frame 10, as outlined above, is designed to receive and lock the sand treating device 22 in operative relation with the screening device and at the same time permit the sand treating device to be quickly removed from the frame so that it may be used individually as a separate unit wherever desired. To permit disengagement of the device 22 from the frame, the base of the main frame is provided with a front extension 31 comprising forwardly converging angle irons 32 and 33 respectively and a front angle bar 34 connecting the members 32 and 33. A suitable base plate 35 is connected to and sup-

ported by the horizontal base portions of the angle irons 32 and 33. This base plate in turn supports and is connected to spaced angle bars 36 and 37. As shown clearly in Figure 2, the rear 5 end of these bars abut and are secured to the front frame section 37' connecting the frame members 13, while the extreme front portions of these bars are suitably secured to the members 32 and 33, respectively.

10 Within the confines of the base of the main frame section 10 and forming a part thereof is a cross bar 38 extending substantially parallel to and in rear of the front frame section 37' and having its ends connected to the side frame 15 members 13 of the base. This constitutes a stop which limits the rear movement of the sand treating device when it is placed in operative position in the frame and as shown in Figures 2 and 6, is of angle iron construction so that the 20 rear rollers 26 of the sand treating device abut the vertical section of the bar.

Spaced side plates 39 are positioned between the bars 37' and 38 and constitute a track upon which the rear rollers 26 are adapted to ride. 25 Secured to the outer longitudinal side portions of these plates are guide rods 40, each of which has its inner face inclined inwardly and rearwardly toward the bar 38. These rods are adapted to guide the rollers 26 in their rearward movement and position the sand treating device correctly in the frame. Secured to each guide adjacent its rear end is a locking bar or element 41 of substantially right angular construction having its horizontal flange 42 extending inwardly over but spaced from the guide 40 sufficiently to permit the extreme outer portion of the rear axle 25 to ride between these two members and to be locked therein against upward movement with respect to the base of the frame. 30 Cooperating with the rear roller guide and locking elements 40 and 42 is a front locking bar 43 having a front vertical wall 44, a top wall 45 and end walls 46. The top wall 45 is also provided with a centrally disposed swivel receiving recess 35 47 which is adapted to embrace the swivel 28 while the top wall 45 extends over the front rollers 30. Figures 2 and 5 clearly show the front locking element 43 in operative position between the bars 36 and 37, and it is retained 40 in this position by suitable cap screws 48 which extend through openings in both the end walls 46 and bars 36 and 37. Suitable nuts 49 are secured to the inner faces of the end walls and receive the threaded shanks of the cap screws.

45 When it is desired to remove the sand treating device from the frame 10, the cap screws 48 are first unscrewed and the locking element 43 is then lifted out of engagement with the swivel, front rollers, and the bars 36 and 37. The device can then be moved forwardly, the rear rollers riding on the plates 39 forwardly of the rear locking element 41 and the front rollers riding forwardly on the plate 35 until they abut the front cross bar 34. In this position the hopper 50 55 21 will be free of the discharge spout 20 and the sand treating device may then be bodily lifted out of the frame by means of a suitable crane or other lifting mechanism (not shown). When it is desired to return the sand treating device 60 to the frame in order that it may be used in conjunction with the screening device, the crane will set the device down into the base of the frame with the front rollers supported on the plate 35 and the rear rollers supported on the 65 plates 39. The device may then be moved rear-

wardly until the rear rollers 26 abut cross rod 38, with the ends of the axle 25 positioned beneath the flanges 42 of the rear locking device 41. The front locking element 43 may then be quickly dropped into position with the swivel 28 5 occupying the recess 47. By inserting and screwing up the cap screws 48 the device is then locked in the frame and may be operated in conjunction with the screening mechanism.

Referring to Figure 3, there is disclosed a modification of the front locking element. In this arrangement the front roller supporting plate and spaced side bars are eliminated. The front extension constitutes forwardly converging side plates 50 which connect with a front plate 51. 15 The rear ends of the plates 50 are secured to the front cross member 51' corresponding to the front section 37'. The locking element 52 is the same as element 43 with the exception that the end walls 53 are inclined so as to extend parallel 20 with the side plates 50 when the locking element is in operative position. Each side plate 50 and end wall 53 is provided with recesses through which a cap screw 54 may be inserted and the inner face of each end wall has secured thereto a suitable nut 55 for receiving the shank of the screw cap.

In Figure 7 there is shown an enlarged view of the lower portion of the sand treating apparatus including the inclined sand belt 23, the 30 hopper 21 and a lower hopper gate 58. This gate is shown in its normally operative position with the gate inclined downwardly and rearwardly at substantially a 45° angle to the belt, instead of being at right angle as is the usual custom. 35 With this construction, the sand will fall from the inclined gate and cannot bridge or pile up against the gate, but will always fall upon and be moved forwardly by the belt. The gate 58 is connected to cross shaft 59 by means of suitable straps 60. The cross shaft is pivoted between opposite walls of the hopper and one end of the shaft is extended forwardly against the outer side of the hopper wall to form a crank 61. The end of this crank is pivotally connected to the forward end of an elongated gate operating rod 62 which extends rearwardly and upwardly and terminates in a curved handle 63. This handle is suitably supported in the upper end of the frame section 14, as shown in Figure 1. The vertical flange 65 is provided with a slot 66 through which the upper end of the handle projects. A stop element 67 is secured to the under side of the handle and this limits the upper and outward movement of the handle. 50 Normally the gate is in its closed position as shown in Figures 1 and 7 with the forward end of the crank 61 resting upon the lateral flange 61' which limits the downward movement of the crank and thus prevents rearward movement of the lower half of the gate. When it is desired to open the gate to discharge accumulated waste material, the handle 63 is grasped and pulled upwardly. This movement raises the crank 61 and swings the lower end of the gate forwardly and upwardly. The stop 67 is so positioned on the rod 62 as to engage the flange 65 when the gate has been opened the desired amount.

It is to be understood that the rod 62 may be discarded if desired, and the gate operated from the crank 61. When the rod 62 is used, however, it is necessary that it be first removed before the sand treating device can be taken from the frame 10. This may be easily and quickly 70 75

done by removing the cotter pin 68 which retains the forward end of the rod 62 upon the crank 61.

The screening device is provided with means for retarding the passage of material lengthwise of the screen. This means comprises a plurality of weighted arms each of which is pivoted to a transverse shaft. These arms are normally supported directly above the screen elements by suitable chains connected at their upper ends to a winding bar pivoted on the frame structure. Referring particularly to Figure 8, there are shown the screening elements 17 and the weighted levers 18, the latter being mounted on the shaft 71 and normally supported by means of suitable chains 72. The upper link of each chain is threaded upon a U-bolt 73 which is secured to one flange of a winding bar 74 of angle stock and this is connected at each end to stub shafts 75 journaled in the frame of the screening device. A rock arm 76 is fastened to one of the shafts 75 and is connected to an operating handle 77 by a suitable link 78. The inner end of the handle is pivoted on the shaft 71. When it is desired to lift the weights as a unit above the screen mechanism, it is merely necessary to grasp the handle 77 and move it downwardly. This rotates the shaft 75, raising the U-bolts 73, chains 72 and the weights 18. With this arrangement in which the handle is pivoted on the shaft 71 and is indirectly connected to one of the stub shafts through link 78 and crank 76, greater leverage is secured and consequently there is a reduction in the pull necessary for raising the weights 18.

It will be observed that the top frame bars 12 support brackets 79 which project outwardly beyond the confines of the frame and terminate in hooks 80. These are for the purpose of lifting and moving the entire apparatus from one point to another as desired.

Such variations from the construction herein shown and described as are within the skill of a mechanic may, of course, be made without departing from the range of my invention.

I claim:—

1. A frame for use in sand conditioning adapted to support a screening mechanism in elevated position, said frame having a base adapted to receive and support a sand treating device having rollers, and roller engaging means detachably carried by the base and adapted to engage the rollers and lock the sand treating device in operative position in the frame below the screening mechanism.

2. A frame for use in sand conditioning adapted to support a screening mechanism in elevated position, said frame having a base adapted to receive and support a sand treating device having front rollers, said base having a pair of spaced bars between which the front rollers are adapted to move and be confined, and means for removably securing the sand treating device in said frame below the screening mechanism including a cross bar engageable with said rollers and detachably connected to said spaced bars.

3. A frame for use in sand conditioning adapted to support a screening mechanism in elevated position, said frame having a base adapted to receive and support a sand treating device having front rollers, said base having a pair of spaced bars for receiving the rollers to support them and the sand treating device for movement from an operative to an inoperative position relative to said screening mechanism, and means including a cross bar of angle iron formation detachably mounted between the spaced bars and

adapted to embrace the rollers for removably securing the sand treating device in operative position.

4. A frame for use in sand conditioning adapted to support a screening mechanism in elevated position, said frame having a base adapted to receive and support a sand treating device having a front swivel and rollers carried thereby, said base having a pair of spaced bars for receiving the rollers to support them and the sand treating device for movement from an operative to an inoperative position relative to said screening mechanism, and means for removably securing the sand treating device in operative position including a cross bar of angle iron formation adapted to embrace the rollers and having a recessed portion for receiving the swivel.

5. A frame for use in sand conditioning adapted to support a screening mechanism in elevated position, said frame having a base adapted to receive and support a sand treating device having front and rear rollers, said base being provided with rear roller supporting plates, locking elements located at the rear of said plates and adapted to retain the rear rollers in engagement with said plates, and means for locking the front rollers in the base whereby the sand treating device is removably secured in said frame in operative position below the screening mechanism.

6. A frame for use in sand conditioning adapted to support a screening mechanism in elevated position, said frame having a base adapted to receive and support a sand treating device having front and rear rollers, said base being provided with rear roller supporting plates, guide members carried by and extending longitudinally of said plates, locking elements located at the rear of said guides and adapted to retain the rear rollers in engagement with said plates, and means for locking the front rollers in the base whereby the sand treating device is removably secured in said frame in operative position below the screening mechanism.

7. A frame for use in sand conditioning adapted to support a screening mechanism in elevated position, said frame having a base adapted to receive and support a sand treating device having front and rear rollers, said base being provided with rear roller supporting plates, guide members carried by and extending longitudinally of said plates, rear roller locking elements of angle iron formation located at the rear of said plates and guides, each locking element having a vertical flange projecting upwardly from the outer side of its respective guide and a horizontal flange spaced from and extending inwardly over the guide and forming therewith a groove for receiving one end of the rear roller axle, and means for locking the front rollers in the base whereby the sand treating device is removably secured in said frame in operative position below the screening mechanism.

8. A frame for use in sand conditioning adapted to support a screening mechanism in elevated position, said frame having a base to receive and support a sand treating device for movement on the base from an operative to inoperative position relative to said screening mechanism, and means carried by said frame for removably securing the sand treating device in operative position.

9. A frame for use in sand conditioning adapted to support a screening mechanism in elevated position, said frame having a base

adapted to removably support a sand treating device having rollers, and tracks on the base for receiving the rollers to support them and the sand treating device for movement from an operative to an inoperative position relative to said screening mechanism whereby the sand treating device may thereafter be removed from the frame.

10. A frame for use in sand conditioning adapted to support a screening mechanism in elevated position, said frame having a base adapted to removably support a sand treating device having rollers, and tracks on the base for receiving the rollers to support them and the sand treating device for movement from an operative to an inoperative position relative to said screening mechanism, and means carried by said base and engageable with said rollers for removably securing the sand treating device in operative position.

11. A frame for use in sand conditioning adapted to support a screening mechanism in elevated position, said frame having a base adapted to removably support a sand treating device below the screening mechanism, and tracks carried by said base for supporting and guiding the sand treating device from an operative to an inoperative position relative to said screening

mechanism whereby the sand treating device may thereafter be removed from the frame.

12. A frame for use in sand conditioning adapted to support a screening mechanism in elevated position, the lower portion of said frame being open and having a base projecting outwardly from the frame and adapted to removably support a sand treating device below the screening mechanism for movement from an operative position within the frame to an inoperative position substantially exteriorly of the frame whereby the sand treating device may thereafter be removed from the frame.

13. A frame for use in sand conditioning adapted to support a screening mechanism in elevated position, the lower portion of said frame being open and having a base projecting outwardly from the frame and adapted to removably support a sand treating device below the screening mechanism for movement from an operative position within the frame to an inoperative position substantially exteriorly of the frame whereby the sand treating device may thereafter be removed from the frame, and means carried by the projecting portion of the base and engageable with the sand treating device for removably securing the latter in operative position.

STANLEY B. DAVIES.
